CLAIM

The ornamental design for a bumper for electronic device, as shown and described.

DESCRIPTION

FIG. 1 is a perspective view including the rear, top, and side of an embodiment of a bumper for electronic device; FIG. 2 is a rear elevation view of the bumper for electronic device of FIG. 1;

FIG. 3 is a front elevation view of the bumper for electronic device of FIG. 1;

FIG. 4 is a side elevation view of the bumper for electronic device of FIG. 1;

FIG. 5 is an opposite side elevation view of the bumper for electronic device of FIG. 1;

FIG. 6 is a bottom plan view of the bumper for electronic device of FIG. 1;

FIG. 7 is a top plan view of the bumper for electronic device of FIG. 1;

FIG. 8 is a perspective view including the front, bottom and side of the bumper for electronic device of FIG. 1; and,

FIG. 9 is a perspective view including the front, top and opposite side of the bumper for electronic device of FIG. 1.

1 Claim, 7 Drawing Sheets
